CLAIM

The ornamental design for a thermostat/hub for climate control and monitoring, as shown and described.

DESCRIPTION

FIG. 1 is a front perspective view of a thermostat/hub for climate control and monitoring, showing our new design in accordance with the invention;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The portions of the thermostat/hub for climate control and monitoring shown in broken lines form no part of the claimed design.
